UNITED STATES PATENT OFFICE.

AMOS H. SMITH, OF NEW YORK, N. Y., ASSIGNOR TO AMERICAN BANK NOTE COMPANY,
A CORPORATION OF NEW YORK.

NUMBERING-HEAD.

1,227,969.

Specification of Letters Patent. Patented May 29, 1917.

Application filed August 22, 1916. Serial No. 116,234.

To all whom it may concern:

Be it known that I, AMOS H. SMITH, a citizen of the United States, residing at the borough of Bronx, city of New York, county 5 of Bronx, and State of New York, have invented certain new and useful Improvements in Numbering-Heads, of which the following is a specification, reference being had therein to the accompanying drawings, 10 which form a part thereof.

My invention relates to numbering heads and more particularly to a type thereof wherein each of the digit wheels is actuated directly from the main actuating means, 15 each wheel of a higher denomination being so controlled as to be held against rotation by the wheel of next lower denomination, except during the transfer operation, the wheels of lower denomination being adapted 20 to release the wheel of next higher denomination when in the operation of the head it is necessary to turn said wheel of higher denomination.

A numbering head made in accordance 25 with my invention possesses all of the characteristics of the type above referred to, but is so constructed and arranged as to be adaptable to a type high numbering head. In a numbering head made in accordance 30 with my present invention, each of the digit wheels excepting the units wheel is positively locked against rotation in either direction excepting when the wheel of next lower denomination has the digit 9 in the 35 printing position at which time the locking mechanism normally preventing the advance of the wheel of next higher denomination, is actuated to release said wheel. To secure the desired compactness of structure, the 40 holding pawl and the locking pawl both act upon the same ratchet or spur wheel and the releasing mechanism is caused to operate directly upon the head of the holding pawl to effect its disengagement from said ratchet or 45 spur wheel. By this construction simplicity in the assembling of the mechanism is possible. Furthermore, each of the digit wheels excepting the units wheel may be an exact replica of every other wheel, the units wheel 50 ordinarily requiring a heavier ratchet by reason of the excessive wear thereupon.

All of the locking pawls are capable of being simultaneously disengaged from their respective ratchet or spur wheels so as to permit quick setting and re-setting of any 55 of the several wheels.

The invention consists primarily in a numbering head embodying therein a sequence of digit wheels, a ratchet or spur wheel carried upon one side of each of said 60 digit wheels and presented toward the wheel of next lower denomination, a cam disk upon the opposite face of each of said wheels, a locking pawl of a width to be operatively engaged by the ratchet or spur 65 wheel of each digit wheel, and the riser of the cam disk of the wheel of next lower denomination, a holding pawl operatively engaging each of said ratchet or spur wheels upon the side thereof opposite to the point 70 of engagement of said locking pawl, a main actuating mechanism and operative connections between said main actuating mechanism and said digit wheels respectively; and in such other novel features of construction and combination of parts as are hereinafter set forth and described and more particularly pointed out in the claims 75 hereto appended.

Referring to the drawings:—

Figure 1 is a side elevation of a numbering head embodying my invention, showing the locking pawls;

Fig. 2 is an end view thereof showing the releasing lever;

Fig. 3 is a section on the line 3—3 of Fig. 1; and

Fig. 4 is a section on the line 4—4 of Fig. 1.

Like letters refer to like parts throughout 90 the several views.

In the embodiment of my invention shown in the drawings, *a* indicates the main frame of the head, having extending therethrough a fixed bearing *b* upon which a plurality of 95 digit printing wheels are rotatably mounted. The number of digit wheels employed may vary as desired. Said digit wheels may all be provided with numerals, or some of them may be provided with numerals and others with 100 key letters or characters. The transfer operation in the type of numbering head to which

this invention relates, is ordinarily automatic as to all of the wheels excepting wheels of denominations of a hundred thousand or more, these wheels ordinarily, being set by hand. This is a common expedient, but is not essential to the invention as the locking and holding mechanisms hereinafter referred to, is applied to the manually operative wheels as well as those which are automatically actuated during the transfer operation.

Loosely mounted upon the shaft b , are a sequence of digit wheels $c-c'-c^2-c^3-c^4-c^5$. Each of said wheels excepting the units wheel c is, or may be, an exact duplicate of the others. Each of the wheels $c-c'-c^2-c^3-c^4-c^5$ has upon one face thereof, (that face presented in the direction of the wheel of lowest denomination) a ratchet or spur wheel $d-d'-d^5$, the teeth or spurs upon each wheel being ten in number and so positioned with relation to the digits upon each wheel, as to insure the positioning of said digits in the printing position upon each actuation of the wheel.

Mounted upon the shaft b is the usual rocking frame f carrying a shaft f' upon which is pivotally mounted a bracket f'' carrying a plurality of ratchet teeth f^3 of graduated heights adapted to coöperate with the respective wheels $d-d'-d^2-d^3-d^4-d^5$ so that during the transfer operation each of said wheels is adapted to be turned through power applied directly thereto from the main actuating mechanism. The pawls f^3 are normally thrust toward the several ratchet wheels by the spring f^4 . The main actuating mechanism and the pawls by which the same is operatively connected with the several digit wheels is old and well known in this art and no claim of invention is made thereto. The swinging frame f is actuated by means of the usual plunger mechanism.

Acting upon each of the ratchet wheels $d-d'-d^2-d^3-d^4-d^5$ is a holding or registering pawl h , the function of which is to prevent a loss of alignment through overrunning of the digit wheels and to secure a slight return movement thereof in the event that there is such an overrunning. Each of said pawls is mounted upon the shaft h' and each has acting thereon its independent spring h^2 .

The units digit wheel c differs from the digit wheels of higher denomination merely in that the ratchet or spur wheel d is heavier than the ratchet or spur wheels upon the other digit wheels to compensate for the additional wear upon this wheel.

Rotably mounted in the frame a is a shaft i , one end of which projects beyond the frame a and is provided with an operating lever handle j . Idly mounted upon the

shaft i are a plurality of locking pawls $k-k'-k^2-k^3-k^4$ adapted to coöperate respectively with the ratchet or spur wheels $d-d'-d^2-d^3-d^4-d^5$. Each of said pawls is thrust toward its ratchet or spur wheel by means of the individual springs $m-m'-m^2-m^3-m^4$ and each of said pawls is adapted to be actuated by means of the shaft i while having movement independently of said shaft sufficient to clear said ratchet or spur wheel. The means of connection between each locking pawl and the shaft i is shown as being a spur n carried by said pawls respectively and moving in a way i' in the shaft i . It is apparent that this arrangement may be reversed so long as each of said pawls is permitted to move the desired distance independently of the shaft i and the rotation of said shaft, will cause the simultaneous movement of all of said pawls away from the ratchet or spur wheel with which said pawls respectively coöperate.

The digit wheels $c-c'-c^2-c^3-c^4-c^5$ respectively have upon the face thereof opposite to that carrying the ratchet or spur wheels $d-d'-d^2-d^3-d^4-d^5$, a cam disk $o-o'-o^2-o^3-o^4-o^5$ having a single riser which will be in the operative relation to the pawls $k-k'-k^2-k^3-k^4$ respectively when the digit 9 upon any of the respective wheels is in the printing position, said riser being of a height to move its coöoperating pawl out of the operative relation to its ratchet or spur wheel and thus permit the free rotation of any particular digit wheel. Hence, the assembled numbering head will have the cam disk of the wheel of lower denomination in close juxtaposition to the ratchet or spur wheel upon the digit wheel of next higher denomination so that by the use of broad locking pawls $k-k'-k^2-k^3-k^4$, said pawls respectively will be in constant operative relation to both a ratchet wheel and a releasing cam. The functions of the wheels $d-d'-d^2-d^3-d^4-d^5$ are four in number. The wheels are turned one tenth of a revolution with each actuation of the main actuating mechanism through the medium thereof; the transfer operations are accomplished by means of the operative connections between the main actuating mechanism and the several digit wheels, through a recess or pocket such as e in each of said wheels; the retard holding or registering pawl acts upon said wheels to prevent a return movement thereof with the actuation of the main actuating mechanism, and the locking pawl acts directly upon this gear so that, except when said locking mechanism is released to set a wheel for the transfer operation, the wheel is firmly held against movement in either direction by the locking mechanism and the holding pawl operative upon that wheel.

By this arrangement, above described, both the holding and the locking mechanisms for the machine may be brought well within the printing surface of the digits upon the 5 digit wheels, thus permitting the utilization of small wheels and of pawls which will be well within the printing frame in a manner to permit the construction of what is known as a type high wheel. Furthermore, the 10 wheels may be brought sufficiently close together to secure the proper spacing of the numbers with small numbering heads while preserving sufficient strength in the various parts to withstand the stresses of the ordinary 15 conditions of use. The showing of the invention in the accompanying drawings is upon a very much enlarged scale being about twice the size of the actual head.

The several wheels $d-d'-d^2-d^3-d^4-d^5$ 20 by reason of the angular spurs thereon (as shown in Fig. 3) act as double ratchet wheels, the holding pawls h being provided with a bevel engaging said spurs in a manner to insure the automatic lifting of said 25 holding pawls as the digit wheel coöperating therewith is turned.

The operation of the herein described numbering head is substantially as follows:

30 Assuming that the numbering head is set to begin a run with the number 1, the locking members or pawls $k-k'-k^2-k^3$ and k^4 will respectively be in engagement with the ratchet or spur wheels $d'-d^2-d^3-d^4$ 35 and d^5 so that each of the wheels $c'-c^2-c^3-c^4$ and c^5 will be positively held against rotation, upon the actuation of the units wheel c through the depression of the plunger g and the resultant actuation of the 40 swinging frame f and the pawl f^3 engaging the units wheel. It is to be observed that the actuation of the wheels $c'-c^2-c^3-c^4-c^5$ is entirely independent of the units wheel except, in so far as the units wheel may 45 control the positioning of the pawls f^3 . In this type of head, the plunger g is depressed, and the numbering head is set for the next actuation of the digit wheel, while an imprint is being made with the numbering 50 head.

When, after repeated actuations of the machine, the digit 9 of the units wheel is being brought to the printing position, the riser upon the cam disk o will engage the head 55 of the rocking pawl k and raise it out of engagement with the ratchet or spur wheel d' of the tens wheel and hold it in this position until the next actuation of the plunger g . The complete disengagement of the 60 said locking pawl will occur substantially simultaneously with the completion of the movement of the units wheel, so that movement of the tens wheels during this interval is prevented.

Upon the succeeding actuation of the plunger g the pawls f^3 coöperating with the ratchet wheels d and d' will simultaneously turn each of the digit wheels c and c' and the riser of the cam disk o passes out of the operative relation to the locking member or pawl k , the spring m of which will immediately force this pawl into engagement with the succeeding tooth or spur upon the ratchet or spur wheel d' ; in which relation it will remain until the digit 9 of the units 70 wheel is again brought to the printing position whereupon the operations above described will be repeated.

As the succeeding digit wheels $c^2-c^3-c^4-c^5$ 80 are brought into play with the arithmetical progression in the numbering operation, the various coöperating locking pawls $k'-k^2-k^3$ and k^4 , ratchet or spur wheels $d^2-d^3-d^4-d^5$ and cam disks $o'-o^2-o^3-o^4$ will be actuated in the same manner above 85 referred to, each wheel of higher denomination being under the immediate control of the wheel of next lower denomination, as to the locking mechanism therefor while being turned directly by the main actuating 90 mechanism.

The cam disk o^5 has no function in the machine as long as this disk is carried by the digit wheel of highest denomination. This disk is used merely as a manufacturing 95 expedient so that all of the digit wheels above the units wheel will be of the same construction, thus simplifying the assembling of the head.

As each digit wheel is turned, the engagement of the teeth or spurs of the ratchet or spur wheel thereon with the coöperating pawl h will, by reason of the bevel surface upon said pawl, permit the rotation of said 100 digit wheel.

The difficulty with numbering heads wherein the transfer is accomplished through the medium of the main actuating mechanism, as distinguished from a mechanism connecting all of the digit wheels of the series is that by reason of the fouling of the wheels there is a tendency of the rotation of a wheel of lower denomination transmitting movement to the wheels of next higher denomination to at least a sufficient extent to result in a loss in alignment of the printing characters. By using the mechanism herein described this condition is made impossible since if any digit 110 wheel of lower denomination than a digit wheel wherein the locking mechanism is released, has any digit other than the 9 in the printing position, the main actuating mechanism or the pawl f^3 operatively connecting said mechanism with the several digit wheels, will be held out of operative relation to said released digit wheel and at least one of the wheels of lower denomination 120 125

will be positively locked by its locking mechanism so as to prevent the transmission of power to the wheel so released.

The spur n of each of the pawls $k-k'$ — k^2-k^3 and k^4 will, as said pawl is caused by its cam disk $o-o'-o^2-o^3-o^4$, to turn upon the shaft i , move in the way i' in said shaft. When it is desired to set or re-set the numbering head, however, all of the pawls $k-k'-k^2-k^3-k^4$ may be simultaneously disengaged from their respective ratchet or spur wheels $d'-d^2-d^3-d^4-d^5$ by turning the shaft i by means of the handle j , thus permitting any of the digit wheels to be turned to any desired extent without the necessity for bringing any other digit wheel into a position with the digit 9 in the printing position; which would be necessary if the automatic releasing means were relied upon when setting or re-setting the head.

It is not my intention in the present application to claim broadly a numbering head provided with a locking mechanism by which each of the digit wheels, excepting the units wheel, is positively locked except during the transfer operation, such type of machines having been heretofore patented by me. The present invention relates merely to a specific mechanism for securing this result.

It is not my intention, however, to limit the invention to the precise details of construction shown, it being apparent that such may be varied without departing from the spirit and scope of the invention.

Having described the invention what I claim as new and desire to have protected by Letters Patent is:—

1. A numbering head embodying therein a sequence of digit wheels, a ratchet or spur wheel carried upon one side of each of said digit wheels and presented toward the wheel of next lower denomination, a cam disk upon the opposite face of each of said wheels, a locking pawl of a width to be operatively engaged by the ratchet or spur wheel of each digit wheel and the riser on the cam disk of the wheel of next lower denomination, a holding pawl operatively engaging each of said ratchet or spur wheels upon the side thereof opposite to the point of engagement of said locking pawl, a main actuating mechanism and operative connections between said main actuating mechanism and said digit wheels respectively.

2. A numbering head embodying therein a sequence of digit wheels, a ratchet or spur wheel carried upon one side of each of said digit wheels and presented toward the wheel of next lower denomination, a cam disk upon the opposite face of each of said wheels, a locking pawl of a width to be operatively engaged by the ratchet or spur

wheel of each digit wheel and the riser on the cam disk of the wheel of next lower denomination, a holding pawl operatively engaging each of said ratchet or spur wheels upon the side thereof opposite to the point of engagement of said locking pawl, means whereby all of said locking pawls may be simultaneously disengaged from their co-operating ratchet or spur wheels to permit the setting of said digit wheels, a main actuating mechanism and operative connections between said main actuating mechanism and said digit wheels respectively.

3. A numbering head embodying therein a sequence of digit wheels, a ratchet or spur wheel carried upon one side of each of said digit wheels, and presented toward the wheel of next lower denomination, a cam disk upon the opposite face of each of said wheels, a rock shaft, a plurality of locking pawls of a width to be operatively engaged by the ratchet or spur wheel of said digit wheels and the riser on the cam disks of the wheels of next lower denomination respectively, said pawls being loosely mounted upon said shaft, co-operating means carried by said shaft and said pawls respectively whereby said pawls are adapted to have movement independently of said shaft or to be moved by said shaft, means whereby said shaft may be actuated, a holding pawl operatively engaging each of said ratchet or spur wheels upon the side thereof opposite to the point of engagement of said locking pawl, a main actuating mechanism and operative connections between said main actuating mechanism and said digit wheels respectively.

4. A numbering head embodying therein a sequence of digit wheels, a double ratchet or spur wheel carried by each of said digit wheels, a plurality of pawls acting upon each of said ratchet wheels whereby the digit wheel carrying said ratchet wheel is normally locked against movement in either direction, means carried by the digit wheel of lower denomination acting upon one of the pawls of the digit wheel of higher denomination whereby said last named digit wheel will be permitted at predetermined intervals to turn in one direction only, a main actuating mechanism and operative connections between said main actuating mechanism and said digit wheels respectively.

5. A numbering head embodying therein a sequence of digit wheels, a ratchet wheel carried by each of said digit wheels having a plurality of angular spurs thereon, a plurality of pawls acting upon each of said ratchet wheels whereby the digit wheel carrying said ratchet wheel is normally locked against movement in either direction, means carried by the digit wheel of lower denomi-

nation acting upon one of the pawls of the digit wheel of higher denomination whereby said last named digit wheel will be permitted at predetermined intervals to turn in one 5 direction only, a main actuating mechanism and operative connections between said main actuating mechanism and said digit wheels respectively.

In witness whereof, I hereunto affix my signature in the presence of two subscribing 10 witnesses, this 1st day of August, 1916.

AMOS H. SMITH.
